Primary Examiner — Jack Reickel
Assistant Examiner — Michael A Kervin(57) **CLAIM**

The ornamental design for a plug puller, as shown and described.

DESCRIPTION

FIG. 1 is a right rear perspective view of a plug puller showing my new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a left rear perspective view thereof;

FIG. 9 is a right front perspective view thereof;

FIG. 10 is a right rear perspective view thereof, shown with environment; and,

FIG. 11 is another right rear perspective view thereof, shown with environment.

The broken line showing of electrical plugs is for the purpose of illustrating environmental structure and forms no part of the claimed design.
